UNITED STATES PATENT OFFICE

CHARLES F. SPLITDORF, OF NEW YORK, N. Y., ASSIGNOR TO ELECTRIC VEHICLE COMPANY, OF JERSEY CITY, NEW JERSEY, A CORPORATION OF NEW JERSEY.

IGNITION-PLUG.

No. 806,017.

Specification of Letters Patent.

Patented Nov. 28, 1905.

Application filed March 7, 1903. Serial No. 146,778.

To all whom it may concern:

Be it known that I, CHARLES F. SPLITDORF, a citizen of the United States, residing in the borough of Manhattan, in the city, county, and State of New York, have invented a new and useful Improvement in Ignition-Plugs, of which the following is a specification.

Bearing in mind the fact that a break or air-gap introduced in the secondary circuit of an induction-coil intensifies the inductive potential thereof, I have devised an ignition-plug for explosive-engines having incorporated in its structure the provision of a gap or air-space intermediate the secondary terminal and the insulated electrode within the plug which terminates in one of the spark-points.

My invention further includes means for accurately gaging and determining the extent of such air gap or break between the terminal and electrode in the secondary circuit in order that such intervening space may be regulated exactly to produce the most satisfactory results.

In the drawing accompanying this application the figure is an elevation of a sparking plug, partly in section and shown as in the secondary circuit of an induction-coil.

In the construction illustrated A indicates the usual bushing inserted within the combustion-chamber of an explosive-engine, the wall of the latter, broken away, being indicated at A'. Also for the purpose of illustration a binding-post, as a, is indicated as containing a terminal a' of the secondary circuit B of an induction-coil, the latter being diagrammatically represented at B'.

A² indicates the usual tubular-threaded portion, which is screwed into bushing A and is provided at its inner end with the electrode a². The threaded sleeve A³ is screwed upon the tubular portion A² to secure the connection of the plug within the bushing.

C indicates the plug-conductor or conducting-rod bearing the electrode c and having the porcelain or other insulating-envelop D.

The parts so far described are substantially as usually employed in the construction of sparking plugs, and the means of making electrical connection between the secondary terminal and the spark-plug electrode consist in securing said terminal in a binding-post which is attached at the outer end of said electrode. In my improved construc-

tion for effecting such electrical connection I provide means in the construction of the terminal binding-post whereby in the adjustment thereof upon the plug an air-space is left between the electrodes, such air-space serving as a spark-gap to be traversed by the electric current in completing the circuit. In my improved construction for the production of said spark-gap I employ an exteriorly-threaded collar F, mounted upon the outer end of insulation D and firmly secured thereto by being spun into the annular recess d.

G indicates an end cap from which extends the binding-post g, having transverse aperture g' to receive the terminal b, which is firmly held therein by screw g². Said cap member G is hollowed at its opposite end, being interiorly threaded to permit of its adjustment upon the threaded collar F, the interior of its cavity being exposed to the atmosphere by means of opening g³, formed through the material of the cap. The interior surface of the cavity in cap G opposite the outer end of electrode C is concaved, so as to be removed from contact with said electrode, and the degree or extent of space 80 formed between the spark-point g⁴ on said surface and the electrode C to regulate the spark-gap is determined by the adjustment of the screw connection between cap G and collar F.

The effect of introducing the aforesaid auxiliary spark-gap in the secondary circuit, either in one of the forms hereinbefore described or in other equivalent constructions, is to intensify the inductive influence of the coil, causing the discharge at the spark-points within the combustion-chamber to have a potential greatly in excess of that hitherto attainable, insuring the production of sparking between said spark-points even when the latter are heavily coated with the products of gaseous combustion, or when the inner face of the plug is coated with a carbonaceous deposit, presenting under ordinary circumstances a path for short-circuiting.

Having now described my invention, I declare that what I claim is—

1. In an ignition-plug for explosive-engines, opposed electrodes located in a secondary circuit of an induction-coil, a plug-conductor or conducting-rod for one of said electrodes, an insulator for said conductor or rod, a metallic cap at the end of said insulator,

the latter being separated from contact with said conductor or rod by an air-space, and a binding-post upon said cap to receive one of the terminals of said circuit.

- 5 2. In a sparking plug included in an electric circuit, an electrode having a sparking-point, an opposed sparking member, an insulating-envelop for said electrode, an exteriorly-threaded collar about the outer end of said envelop, an open metallic cap adjustably screwed upon said collar to provide an air-space between said cap and electrode, and a binding-post upon said cap, a terminal of the circuit being connected to said binding-post.
- 15 3. Sparking mechanism comprising a plug with a pair of electrodes or terminals at each of two separate portions thereof to form spark - gaps, and provisions whereby said plug may be attached to an engine-cylinder
- 20 with one pair of terminals visible.
4. Sparking mechanism comprising a plug with electrodes or terminals at each end to form spark-gaps.
5. A plug for combustion-engines, having
- 25 a plurality of pairs of stationary electrodes,

each forming a spark-gap, and means whereby said plug may be secured to an engine with one pair of electrodes in active igniting position, and the other pair visible.

6. Sparking mechanism for combustion- 30 engines having two stationary sparking gaps in series in stationary relationship, one of said spark-gaps being located within the engine-cylinder, and the other outside the same.

7. An igniting mechanism for combustion- 35 engines comprising a circuit having two pairs of stationary electrodes or terminals in series, each pair separated to form a spark-gap, one pair of electrodes or terminals being located within the cylinder and the other being located externally thereto in position to be observed by the operator.

In testimony whereof I have signed my name to this specification, in the presence of two subscribing witnesses, this 2d day of 45 March, 1903.

CHARLES F. SPLITDORF.
